UNITED STATES PATENT OFFICE.

SAMUEL SILBERSTEIN, OF PITTSBURG, PENNSYLVANIA.

DESIGN FOR A CONDUCTOR FOR WATER.

SPECIFICATION forming part of Design No. 23,227, dated April 24, 1894.

Application filed January 5, 1894. Serial No. 495,871. Term of patent 7 years.

To all whom it may concern:

Be it known that I, SAMUEL SILBERSTEIN, a citizen of the United States, residing at Pittsburgh, in the county of Allegheny and 5 State of Pennsylvania, have invented or discovered certain new and useful Improvements in a Design for Conductors for Water, &c., of which improvements the following is a specification.

10 The design described herein relates to conductors for water, &c.

In the accompanying drawings forming a part of this specification, Figure 1 is an end view of my design for conductors, and Fig. 2

15 is a side elevation of the same.

The leading features of my design consist in the longitudinally corrugated body portion which is substantially circular in cross sec-

tion and the dovetail or the undercut longitudinal projection merging its sides into the 20 corrugated portion. The conductor 1 substantially circular in cross section is corrugated longitudinally nearly around its circumference, and has a dovetailed or undercut projection 2, the walls of the projection 25 merging with the wall of the body of the conductor by a reverse curve.

I claim herein as my invention—

The design for conductors for water, &c., substantially as herein shown and described. 30

In testimony whereof I have hereunto set my hand.

SAMUEL SILBERSTEIN.

Witnesses:

DARWIN S. WOLCOTT,
F. E. GAITHER.
